(57) **CLAIM**

The ornamental design for a kiln brick protective collar with adjustable tabs, as shown and described.

DESCRIPTION

FIG. 1 is a perspective view of a kiln brick protective collar with adjustable tabs showing my design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof; and,

FIG. 8 is an exploded view thereof.

The broken lines in the drawings depict portions of the kiln brick protective collar with adjustable tabs that form no part of the claimed design.

1 Claim, 4 Drawing Sheets
